UNITED STATES PATENT OFFICE.

BAILEY M. FENNELL, OF CRISTOBAL, CANAL ZONE, ASSIGNOR OF ONE-HALF TO
JAMES A. SMITH, OF BRISTOL, TENNESSEE.

ENVELOP.

1,111,690.

Specification of Letters Patent. Patented Sept. 22, 1914.

Application filed December 27, 1912. Serial No. 738,897.

To all whom it may concern:

Be it known that I, BAILEY M. FENNELL, a citizen of the United States, residing at Cristobal, Canal Zone, Panama, have invented certain new and useful Improvements in Envelops; and I do hereby declare the following to be a full, clear, and exact description of the invention, such as will enable others skilled in the art to which it appertains to make and use the same.

This invention relates to new and useful improvements in mailing envelopes, especially that class in which provision is made for utilizing the same envelop for return use.

15 The chief object of the invention is to provide an envelop of the type described wherein means is provided for disclosing upon the face of the envelop a plurality of surfaces adapted to receive addresses.

20 A further object lies in the provision of such a device which will be efficient in use and shall yet possess such a simple design as to permit ready and economical manufacture.

25 With these and other objects in view, the invention resides in the novel combination, formation and arrangement of parts more fully described in the following specification and particularly pointed out in the appended claim.

Reference is had to the accompanying drawings, wherein similar characters of reference designate corresponding parts throughout the several views and in which:

35 Figure 1 is a front elevation of an envelop with my device applied thereto. Fig. 2 is a rear elevation of the envelop with the back thereof broken away to more fully disclose the invention. Fig. 3 is a section on the line 3—3 of Fig. 1, and Fig. 4 is a blank from which the address slip is formed.

40 Referring to the drawings, 10 designates a usual envelop to which is applied a preferred form of the invention. The envelop is provided on its face 11 with a pair of spaced parallel longitudinally extending slits 12.

An address slip 13 is provided substantially rectangular in shape and having its upper end 14 tapered to a point. This address slip is trained through the slits from the interior of the envelop so that by sliding the slip through the slits a fresh surface is

provided on the face of the envelop. To prevent withdrawal of the bottom of the slip through the slits there is provided on the 55 lower extremity of the slip a pair of lateral extensions 15. These extensions bear against the ends of the lower slit and perform the function above mentioned.

To protect the slip a shield 16 is provided, 60 which is substantially the width of the envelop and which is secured at each side to the inner surface of the face thereof. The address slip, when in its lower position, is bent over the shield on the dotted line 17. 65 When the address slip is positioned in its raised position, it is bent over the top of the shield on the line 18.

When the envelop is mailed the address slip is in its lower position and the address 70 of the receiver is written on the surface thereof exposed between the slits 12. When it is desired to readdress the envelop, the address slip is raised and bent down on the line 18, thus providing an entire fresh ad- 75 dressing surface.

It is thus seen that an exceedingly simple device is provided which will perform all of the functions desired in a highly satisfactory manner.

80 What is claimed is:

The combination with an envelop provided with a pair of longitudinally spaced parallel slits in its face, of an addressed slip substantially rectangular in shape and slidably 85 trained through the slits and adapted to contain a pair of addresses to selectively expose one, a pair of lateral extensions on the bottom of the slip forming stops to limit the sliding movement of the slip in the slits 90 and a shield provided adjacent the inner sides of the face of the envelop and secured thereto, said shield being substantially of the same width as the envelop and the upper end of the address slip being bent down 95 upon the shield to hold said slip against sliding movement when the flap of the envelop is closed.

In testimony whereof, I affix my signature, in the presence of two witnesses.

BAILEY M. FENNELL.
